(57) CLAIM

The ornamental design of a column, as shown and described.

DESCRIPTION

The disclosed column may be used in decking and/or other applications.

The FIGURE is a front view of the column of the present invention, the rear view, right side view, and left side view being identical to the front view.

The top and bottom of the column of FIG. 1 form no part of the claimed design.

1 Claim, 1 Drawing Sheet

The Figure
